SHOE SUPPORTING JACK

Alfred R. Morrill, Beverly, Mass., assignor to
United Shoe Machinery Corporation, Flemington, N. J., a corporation of New Jersey

Application June 3, 1942, Serial No. 445,551

9 Claims. (Cl. 12—127)

The present invention relates to shoe supporting jacks for use in the manufacture of shoes and more particularly to an improved means for actuating the tilting last pin commonly used in shoe supporting jacks to clamp a shoe in position on the jack.

The invention is herein disclosed as embodied in a shoe supporting jack of the type disclosed in applicant's pending application Serial No. 367,587, filed November 28, 1940, comprising a toe rest, a heel support movable towards and from the toe rest, a last pin carrier pivotally mounted in the heel support, and a jacking lever and connections actuated thereby, for tilting the last pin carrier to press the toe of the shoe against the toe rest.

The present invention consists in an improved means comprising a longitudinally movable wedge for tilting the last pin carrier commonly used in shoe supporting jacks and for locking the carrier against backward movement, and it is to be understood that, except as defined in the claims, the invention is not limited to use in the particular type of shoe supporting jack disclosed in applicant's prior application but may be employed to advantage in any form of jack having a tilting last pin for clamping a shoe against the toe rest of the jack.

Referring to the drawings, in which is illustrated a shoe supporting jack provided with a last pin tilting and locking mechanism embodying one form of the various features of the present invention, Fig. 1 is a view in elevation, and partly in section, of the shoe supporting portion of the jack, with the parts in positions ready for the reception of a lasted shoe; Fig. 2 is a similar view but illustrating the lasted shoe in clamped position on the jack; Fig. 3 is a detailed sectional view on an enlarged scale illustrating the construction of the parts shown in Fig. 2; and Fig. 4 is a detail cross-sectional view taken on a plane indicated by the line 4—4 of Fig. 3.

Except as hereinafter described, the jack illustrated in the drawings comprises parts constructed and arranged to operate as fully illustrated and described in applicant's pending application above referred to. As illustrated, the jack comprises a toe rest indicated at 2 and a heel support indicated at 4. The toe rest 2 is pivotally mounted at 6 on the jack frame 8 so as to be capable of a vertical adjustment for shoes of different sizes. The heel support 4 is in the form of a slide and is mounted in guideways 1 (see Fig. 4) in the jack frame so as to be movable towards and from the toe rest. To locate the shoe lengthwise in the jack, a toe gage indicated at 10 is fixed in the jack frame in position to engage the toe end of the shoe and stop the shoe in the desired position as the heel support with the shoe thereon is moved towards

the toe rest. During this movement of the heel support, the toe rest is adjusted vertically to the desired height by means of a rod 12, the forward end of which is arranged to slide between suitably shaped surfaces on the jack frame and underside of the toe rest 2 and the rear end of which is pivotally connected to the heel support 4.

At the toe rest end of the jack frame is a pair of toe grips or clamps 14 between which the toe of a shoe is located and held in proper position laterally of the jack frame. Mechanism is provided for moving the toe grips towards and from each other, which mechanism includes plungers 16, a pinion shaft 18 extending horizontally between each plunger 16 and meshing with a rack 20 mounted for lengthwise sliding movement in the jack frame 8. When the rack slides in the frame, the pinion shaft is rotated and the plungers 16 are moved against the lower ends of levers

20 supporting the toe grips to cause the toe grips to be brought together into contact with the toe end of a shoe on the jack. Movement is imparted to the rack through a locking pawl 22 cooperating with ratchet teeth 23 on the rack.

25 The pawl is mounted upon the eccentric hub of a hand operated jacking lever 24 pivotally mounted upon a pivot pin 26 in the forward end of the heel support slide, a spring 28 being provided to hold the pawl in engagement with teeth 23 on the under surface of the rack. At the outer end of the heel support slide is a last pin carrier 30 pivotally mounted upon a horizontal pin 32 and provided with an upwardly projecting last pin 34. The lower portion of the last pin carrier 30 is slotted to receive an actuating arm 36 which is pivotally supported at its upper end upon the pin 32.

30 To press the toe of a shoe on the jack against the toe rest, the last pin carrier 32 is tilted to force the last pin towards the toe rest and to enable the jacking lever to tilt the last pin carrier, the lever is connected by a link 38 which, together with the jacking lever, forms a toggle. When the toggle is straightened, the last pin and carrier are tilted to clamp the shoe. As thus far described, the construction and operation of the illustrated jack are the same as that of the application above referred to.

35 In the jack of the application, the lower end of the last pin carrier is provided with ratchet teeth similar to those indicated in the present drawings at 40 arranged to be engaged by an actuating pawl pivotally mounted on an arm of the prior jack corresponding to the arm 36 of the present jack. Due to the relatively wide spacing of the teeth on the lower end of the last pin carrier, and the relatively small movement imparted to the actuating pawl by the toggle including the link 38, a substantial variation may 40 occur in the force with which the last pin and

carrier are tilted towards the toe rest and as a result, in some instances, the lasted shoe may be insecurely clamped in place on the jack. If small ratchet teeth with narrower spacings are employed on the last pin carrier, there is danger of breakage or injury to the teeth as a result of the heavy pressures required in clamping the shoe. In order to offset the possibility of looseness of the shoe after being clamped on the jack in the application, a holding pawl separate from the actuating pawl is provided so that if the first movements of the jacking lever and connected toggle are insufficient to clamp the shoe securely, the actuating lever can again be operated a short distance to bring the actuating pawl against a new ratchet tooth on the last pin carrier, the holding pawl preventing the last pin carrier from releasing the shoe during this operation. If the jacking lever of the application is then moved to straighten the toggle including the link 38, the actuating pawl tends to tilt the last pin carrier with greater force and a further distance corresponding to the length of the new ratchet tooth. Even by operating the jacking lever more than once, as indicated, there is no positive assurance in the prior jack that the shoe will be held securely under all conditions, particularly if the shoe is insecurely located on the jack before clamping.

To obviate these difficulties in the construction of the present illustrated jack, the ratchet teeth 40 on the last pin carrier 30 are engaged by a single pawl 42 only pivotally mounted on the actuating arm 36 so as to enable engagement and disengagement from the ratchet teeth. To actuate the pawl towards and from the ratchet teeth and to move the pawl in a direction to tilt the last pin and carrier, the pawl 42 is provided with projections 44 and 46 acting against a lengthwise movable wedge 48 and a wedge supporting surface 50 on the heel support slide, respectively. The wedge 48 is mounted within a slot of the heel support slide and moves along the surface 50 towards and from the last pin carrier pivot pin 32. When raised towards the pivot pin 32, the wedge engages the projection 44, first swinging the pawl 42 about its pivot into engagement with the ratchet teeth and then moving the pawl bodily to tilt the last pin and carrier, thus clamping the toe of a shoe on the jack firmly against the toe rest. The lower end of the wedge is slotted longitudinally of the wedge to receive one arm of a lever 52 having a transverse pin 54 fitting within notches at the sides of the slot in the wedge. The lever 52 is fulcrumed on a pin 56 in the heel support slide and has in its other arm a pin 58, the ends of which enter slots in a forked end of the link 38.

To impart a yielding shoe clamping movement to the wedge 48, a compression spring 60 (Fig. 3) is mounted within a recess in the link 38 and acts on a plunger 62 at the outer end of the recess, which plunger engages the surface of the lever 52, the arrangement being such that when the actuating lever is operated to clamp a shoe on the jack, the wedge 48 will be raised yieldingly along the supporting surface 50 without causing the pin 58 to engage the ends of the slots in the link 38, even under the most extreme conditions. The strength of the spring 60 is sufficient to raise the wedge 48 with a shoe clamping force and to hold the wedge from reverse movement. The angle of the wedging surface on the wedge, together with the force of the spring 60, for all practical purposes, act as an irreversible lock in

positively preventing the shoe from being loosened or unclamped. The spring itself through the wedge also will take up automatically any looseness in the shoe clamping mechanism which results from insecure location of the shoe on the jack before clamping.

When the shoe is to be unclamped, the jacking lever is moved from the position of Figs. 2 and 3 into the position of Fig. 1 to break the toggle comprising link 38 and the jacking lever and to cause the wedge 48 to be lowered along the supporting surface 50. The first downward movement of the wedge causes the clamping pressure of the last pin on the shoe to be relieved. Thereafter, further downward movement of the wedge causes the projection 46 on the pawl 42 to be moved, by means to be described, towards the wedge supporting surface 50 and the pawl to be disengaged from the ratchet teeth 40. To insure positive disengagement of the pawl from the ratchet tooth, a lug on the arm 36 is acted upon by a plunger 64 backed by a relatively strong spring 66 coiled within a recess in the heel support slide. The force of the spring 66 tends to swing the pawl carrying arm 36 towards the wedge support surface 50, thereby positively pressing the pawl away from the ratchet teeth 40. As soon as the pawl is disengaged from the ratchet teeth, the last pin 34 and carrier 30 are tilted outwardly away from the toe rest by a leaf spring 68 mounted within the slot of the last pin carrier and having its lower end made fast to the pawl arm 36. The outward tilted position of the last pin carrier is limited by the engagement of the lower end of the carrier against the wedge supporting surface 50, as indicated in Fig. 1. When in this position, the last pin is ready for the reception of a new shoe.

After applying a new shoe to the last pin and during movement of the toe of the shoe by the operator downwardly against the toe rest, the last pin is tilted slightly into a preliminary position. Thereafter, movement of the jacking lever into shoe clamping position (Figs. 2 and 3) causes a uniform irreversible clamping movement to be imparted to the last pin carrier, the last pin tilting forcibly towards the toe rest and bringing the shoe into securely clamped position. If the shoe is insecurely located on the jack during the preliminary and final clamping movements imparted to the last pin, after the spring 60 takes up the resulting looseness in the shoe, the wedge will prevent release even if heavy pressures are applied to the shoe during further operations. In this way, the spacings between the ratchet teeth may be made sufficiently wide to insure suitable strength with which the shoe is clamped and held from displacement on the jack. Also, no special attention is required on the part of the operator, after clamping the shoe, to insure that no looseness exists between the shoe and the jack before initiating further operations on the shoe.

The nature and scope of the present invention having been indicated, and constructions embodying the several features of the invention having been specifically described, what is claimed is:

1. A shoe supporting jack for use in the manufacture of shoes comprising a frame, a toe rest mounted on the frame, a heel support, a last pin, a last pin carrier mounted to tilt on the heel support and press the toe of a lasted shoe placed on the jack against the toe rest, devices comprising a ratchet and cooperating pawl for holding the last

pin carrier in tilted position, a jacking lever, an endwise movable wedge acting on said devices arranged when moved in one direction to tilt the last pin carrier to clamp the shoe on the jack, yielding connections from the jacking lever to the wedge for moving the wedge in one endwise direction, and means for supporting the wedge arranged to lock the wedge from movement in the opposite endwise direction.

2. A shoe supporting jack for use in the manufacture of shoes comprising a frame, a toe rest mounted on the frame, a heel support, a last pin, a last pin carrier mounted to tilt on the heel support and press the toe of a lasted shoe placed on the jack against the toe rest, an endwise movable wedge, means actuated by an endwise movement of the wedge in one direction for tilting the last pin carrier and for holding the carrier in tilted position, yielding means for moving the wedge in said direction, and means for supporting the wedge arranged to lock the wedge from movement in the opposite direction against backward pressure exerted from the last pin carrier on the wedge.

3. A shoe supporting jack for use in the manufacture of shoes comprising a frame, a toe rest mounted on the frame, a heel support, a last pin, a last pin carrier mounted to tilt on the heel support and press the toe of a lasted shoe placed on the jack against the toe rest, a ratchet on the last pin carrier, an arm pivotally mounted on the heel support, a pawl mounted on the arm and arranged to engage the ratchet, a jacking lever, connections including a yielding member for imparting to the arm a movement in a direction to tilt the last pin carrier towards the toe rest and for imparting a movement to the arm in the opposite direction to tilt the last pin carrier away from the toe rest, and means acting during the movement of the arm in said opposite direction to disengage the pawl from the ratchet.

4. A shoe supporting jack for use in the manufacture of shoes comprising a frame, a toe rest mounted on the frame, a heel support, a last pin, a last pin carrier mounted to tilt on the heel support and press the toe of a lasted shoe placed on the jack against the toe rest, a ratchet on the last pin carrier, an arm pivotally mounted on the heel support, a pawl mounted on the arm and arranged to engage the ratchet, a jacking lever, connections from the jacking lever for imparting to the arm a movement in a direction to tilt the last pin carrier towards the toe rest, a comparatively strong spring acting on the arm for moving the arm in a direction to cause the pawl to slide idly along the ratchet and to unclamp the shoe, and a comparatively weak spring acting on the last pin carrier in a direction to unclamp the shoe when the arm is moved by the strong spring.

5. A shoe supporting jack for use in the manufacture of shoes comprising a frame, a toe rest mounted on the frame, a heel support, a last pin, a last pin carrier mounted to tilt on the heel support and press the toe of a lasted shoe placed on the jack against the toe rest, devices for locking the carrier in tilted position comprising a longitudinally movable wedge, and devices intermediate the carrier and wedge engaged by the wedge and arranged to be actuated by the wedge when moved in one direction to tilt the carrier, yielding means for moving the wedge in said direction, and means for supporting the wedge against pres-

sure exerted on the wedge from the last pin carrier by said devices.

6. A shoe supporting jack for use in the manufacture of shoes comprising a frame, a toe rest mounted on the frame, a heel support, a last pin, a last pin carrier mounted to tilt on the heel support and press the toe of a lasted shoe placed on the jack against the toe rest, an endwise movable wedge, a ratchet on the last pin carrier, an arm pivotally mounted on the heel support, and a pawl mounted on the arm and arranged to engage the ratchet and to be actuated by an endwise movement of the wedge in one direction for moving the pawl into engagement with the ratchet and then by a continued movement in the same direction for moving the pawl arm to tilt the last pin carrier towards the toe rest.

7. A shoe supporting jack for use in the manufacture of shoes comprising a frame, a toe rest mounted on the frame, a heel support, a last pin, a last pin carrier mounted to tilt on the heel support and press the toe of a lasted shoe placed on the jack against the toe rest, an endwise movable wedge, a ratchet on the last pin carrier, an arm pivotally mounted on the heel support, a pawl mounted on the arm and arranged to engage the ratchet and to be actuated by an endwise movement of the wedge in one direction for moving the pawl into engagement with the ratchet and then by a continued movement in the same direction for moving the pawl arm to tilt the last pin carrier towards the toe rest, and means for disengaging the pawl from the ratchet during return movement of the pawl arm.

8. A shoe supporting jack for use in the manufacture of shoes comprising a frame, a toe rest mounted on the frame, a heel support, a last pin, a last pin carrier mounted to tilt on the heel support and press the toe of a lasted shoe placed on the jack against the toe rest, an endwise movable wedge, a ratchet on the last pin carrier, an arm pivotally mounted on the heel support, a pawl mounted on the arm and arranged to engage the ratchet and to be actuated by an endwise movement of the wedge in one direction for moving the pawl into engagement with the ratchet and then by a continued movement in the same direction for moving the pawl arm to tilt the last pin carrier towards the toe rest, a supporting surface on the heel support along which the wedge moves, and a projection on the pawl arranged to engage the wedge supporting surface of the heel support to disengage the pawl from the ratchet during return movement of the pawl arm.

9. A shoe supporting jack for use in the manufacture of shoes comprising a frame, a toe rest mounted on the frame, a heel support, a last pin, a last pin carrier mounted to tilt on the heel support and press the toe of a lasted shoe placed on the jack against the toe rest, devices for locking the carrier in tilted position comprising a longitudinally movable wedge, and devices intermediate the carrier and wedge engaged by the wedge and arranged to be actuated by the wedge when moved in one direction to tilt the carrier, means for supporting the wedge against pressure exerted on the wedge from the last pin carrier by said intermediate devices, a jacking lever and a toggle actuated by the jacking lever, and a lever having one arm connected to the toggle and another to the wedge for moving the wedge in a direction to tilt the last pin towards the toe rest.
